TOY BEAUTY STATION

Rouben T. Terzian and Marvin I. Glass, Chicago, Ill., assignors to Marvin Glass & Associates, Chicago, Ill.

Filed Jan. 29, 1973, Ser. No. 327,416

Term of patent 14 years

Int. Cl. D21—01

U.S. CL. D34—15 AC

FIG. 1 is a top plan view of a toy beauty station showing our new design;

FIG. 2 is a front elevational view thereof;

FIG. 3 is a rear elevational view thereof; and

FIG. 4 is a side elevational view thereof, the side opposite being a mirror image.

We claim:

The ornamental design for a toy beauty station, as shown and described.
